(57) **CLAIM**

The ornamental design for a short sprinkler, as shown and described.

DESCRIPTION

FIG. 1 is a front perspective view of a sprinkler according to the invention;

FIG. 2 is a front elevational view of the sprinkler of FIG. 1, the rear elevational view being identical;

FIG. 3 is a side elevational view of the sprinkler of FIG. 1, the left side being the same except for the omission of the hose connection; and,

FIG. 4 is a bottom plan view of the sprinkler of FIG. 1. The broken line showing is for illustrative purposes only and forms no part of the claimed design.
